US0D1113584S

(12) **United States Design Patent** (10) Patent No.: **US D1,113,584 S**
(45) Date of Patent: ** Feb. 17, 2026

(54) **FRAME OF CARGO BIKE**

(71) Applicant: **Shenzhen Xunlu Innovation Technology Co., Ltd.**, Shenzhen (CN)

(72) Inventors: **Zhuo Guo**, Shenzhen (CN); **Xin Hao**, Shenzhen (CN)

(73) Assignee: **SHENZHEN XUNLU INNOVATION TECHNOLOGY CO., LTD.**, Shenzhen (CN)

(**) Term: **15 Years**

(21) Appl. No.: **29/944,160**

(22) Filed: **May 27, 2024**

(30) **Foreign Application Priority Data**

Dec. 1, 2023 (CN) 202330792494.1

(51) **LOC (15) Cl.** **12-11**

(57) **CLAIM**

The ornamental design for a frame of a cargo bike as shown and described.

DESCRIPTION

FIG. 1 is a left side elevation view of a frame of cargo bike showing my new design;

FIG. 2 is a right side elevation view thereof;

FIG. 3 is a rear elevation view thereof;

FIG. 4 is a front elevation view thereof;

FIG. 5 is a top plan view thereof;

FIG. 6 is a bottom plan view thereof;

FIG. 7 is a top, front, and right side perspective view thereof; and,

FIG. 8 is a top, front, and right side perspective view of the frame of cargo bike in its state of use thereof.

The dash-dash broken lines in the drawings depict portions of the frame of cargo bike that form no part of the claimed design.

1 Claim, 4 Drawing Sheets
